UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TRIMMING MECHANISM FOR SEWING MACHINES.

Original application filed January 27, 1917, Serial No. 144,847. Divided and this application filed June 22, 1918. Serial No. 241,368.

To all whom it may concern:

Be it known that I, ALBERT H. De Voe, a citizen of the United States, residing at Westfield, in the county of Union and State 5 of New Jersey, have invented certain new and useful Improvements in Trimming Mechanisms for Sewing Machines, of which the following is a specification, reference being had therein to the accompanying drawings.

This invention relates to a trimming mechanism, such as that shown in my copending application Serial No. 144,847, filed January 27, 1917, of which this application 15 is a division.

It has been common to support the blades of the trimming mechanism on a rigid presser-foot. When such a presser-foot meets a seam or other irregularity in the material being sewed it is abruptly raised and held so until the irregularity is passed when it is abruptly lowered. As the trimmer-blades are raised and lowered simultaneously with the presser-foot, abrupt projections 20 are formed in the cut edge portions of the material of a length equal to that of the presser-foot. In order that the seam may be closed at each side of these projections the material constituting them must be crowded or bunched together, resulting in 25 unsightly and uneven work.

The object of the present invention is to provide a trimming mechanism which will trim the meeting edge portions of material 30 with the greatest possible uniformity under varying conditions, such as irregularity in the thickness of the material, cross-seams, &c., whereby a strong flat seam may be produced.

40 In the present embodiment the presser-foot has a shank provided with a flat extension and a pivoted sole portion arranged side by side. The sole portion is slotted to provide spaced toes between which the upturned edge portions of material are guided to a trimmer, the latter consisting of a ledger-blade secured to the flat extension and spaced slightly from the sole portion, and a cutting blade mounted on a vibratory 45 arm at the lower end of a rock-shaft journaled in the machine head. This rock-shaft is spring-pressed downwardly and is oscillated by a link connection to an arm on the needle-actuating lever.

Referring to the drawings, Fig. 1 is a 55 side elevation partly in section and with the supporting means partly broken away, showing a feed-off-the-arm sewing machine with my trimming mechanism applied thereto. Fig. 2 is a rear elevation of the machine 60 frame partly in section and with parts broken away. Fig. 3 is a plan of the presser-foot and trimming blades showing the presser-bar in section. Fig. 4 is a perspective of the presser-foot and trimmer. Fig. 65 5 is a section through the trimmer on the line 5—5 of Fig. 4, but showing the trimmer-blades closed.

As shown in the drawings, the machine 70 frame includes a depending support 1 secured at its upper end in any desired way, and enlarged laterally at its lower end to form a body portion 2 in which is mounted in suitable bearings a main-shaft 3 carrying a pulley driven by a belt (not shown) connected to a drive pulley located at the upper end of the support 1. Extending downwardly and rearwardly from the body 2 75 is a hollow L-shaped work-arm 4 comprising a vertical portion 5 and a horizontal portion 80 6 carrying the throat-plate 7. Mounted in the arm and driven from shaft 3 are a looper mechanism and feed-dogs which form no part of the present invention. Disposed above the work-arm is a head 8 carried by a 85 bracket-arm 9 connected to the body 2, the arm 9 being arranged at one side of the center line of the work-arm, whereby the operator may have an unobstructed view of the work. The shaft 3 carries a spherical- 90 shaped crank 10 connected by a link 11 at 12 to one end of a needle-actuating arm 13 fulcrumed at 14 on the bracket-arm. The other end of the needle-arm 13 has a pivotal 95 connection at 15 with a link 16 pivotally connected to a split sleeve 17 on a needle-bar 18, the latter carrying at its lower end pairs of needles 19 and 20. Mounted to slide in the bearing sleeve 21 is a presser-bar 22, which carries at its upper end a horizontal 100 socket member 23, and within said socket-member is fixed a pin 24 which supports at one end a vertical guide-sleeve 25 slidable on a trimmer-actuating rock-shaft 26 to be presently described. At its opposite end pin 105 24 is reduced and carries two roller-disks 27, 28, the first of which supports one end of a leaf-spring 29 the other end of which is

apertured and fits over a pin 30. The pressure of the spring 29 may be regulated by a screw 31 carried by the bracket-arm 9. The disk 28 bears against a cam 32 on the manually operated presser-foot lifting lever 33 pivoted within the head 8, said lever projecting through a slotted opening in the head. A guide-block 34 is mounted on the lower end of the presser-bar, said block being slotted to slidably engage the flattened sides 35 of the downwardly extending end of a bearing sleeve 36 fixed in the head 8. The guide-block has a depending lug 37 to which is secured by screws 38 the shank 39 of the presser-foot. Pivotedly mounted on the shank 39 by means of the pin 40 is a sole-piece 41. The forward extremity of the sole-piece is slotted longitudinally at 42 to form spaced toe portions 43, and it has a heel portion 43^a (Fig. 1) extending rearwardly from its pivot. The central portion of the sole-piece is apertured at 44 to receive the needles 19. Apertures 45 are provided for the rear needles 20. Carried by the shank 39 is a flattened extension 46, which is transversely recessed to receive the ledger-blade 47 of the trimming mechanism, said blade being secured therein by screws 48. The block 34, lug 37 and shank 39 with its extension 46 form the body portion of the presser-foot. The toe portions of the sole-piece 41 project slightly beyond the extension 46. The left-hand toe portion 43 is reduced in thickness at 43' to allow the ledger-blade to be set close to the surface of work passing under the presser-foot. The ledger-blade is spaced above the sole-piece, when operating on work of uniform thickness. The cutter-blade 49 is secured by screws 50 to the forwardly extended free end of a bowed arm 51 whose opposite sleeved end is secured to the lower end of the trimmer-actuating rock-shaft 26 above referred to. The rock-shaft is journaled in sleeves 36 and 53 in the head 8 and has secured thereto a split collar 54 from which projects a ball-ended pin 55, the latter being embraced by one strapped end of a link 56 whose opposite strapped end (Fig. 1) embraces a ball-ended pin 57 carried by a short arm 58 projecting upwardly from the needle-arm 13. A coil spring 59 is interposed on shaft 26 between the bearing sleeve 53 and the split collar 54, said spring serving to yieldingly maintain the cutter-blade in contact with the ledger-blade, while allowing the latter to move vertically for varying thicknesses of material. Both trimmer-blades can also move upwardly with the presser-foot when the latter is lifted for any reason.

It will also be noted from an inspection of Fig. 5 that the lower face of the extension 46 is higher than the lower face of the pivoted sole-portion 43 so that in normal operation when the lower face of the sole-portion

43 is in contact with the surface of the work it maintains the extension 46 spaced above the work. Preferably the entire weight of the presser-foot is carried by the sole-portion. 70

The improved trimming mechanism operates as follows—

As an irregularity in the material, for instance a cross-seam, reaches the toes 43 of the sole-piece and passes thereunder the 75 toes are raised a given distance, but the trimmer-blades will at first be lifted but a fraction of this distance and will trim the upturned portions of material at a gradually increasing distance from the throat- 80 plate as the cross-seam approaches the pivot 40 due to the fact that as the irregularity passes under the front end of the sole-portion, this sole-portion turns on the pivot 40 and this pivot with the fixed extension 85 46 and the trimming mechanism is at first raised only a slight amount instead of the full height of the irregularity as would be the case if the sole-portion were rigid with the extension 46 or if this extension 90 rested on the surface of the work. After the cross-seam passes the pivot the heel portion 43^a of the sole piece is raised and the toe-portion tilts toward the throat-plate once 95 more, and the trimming action takes place at a gradually decreasing distance from the throat-plate until the cross-seam passes entirely from under the presser-foot. As a result, the projecting portions in the adjacent 100 cut edges caused by the cross-seam are at their maximum only immediately adjacent said seam and taper away gradually to each side for a distance approximately half the length of the presser-foot, and a comparatively smooth seam can be formed without 105 any sudden bunching and crowding together of the material. With the previously used rigid presser-foot and trimmer carried thereby, the entire presser-foot is immediately raised to a maximum distance by a 110 cross-seam, carried at this height until the seam leaves the presser-foot and then as suddenly lowered, with the result that there are abrupt projections formed in the cut edges of the material extending for approximately 115 the entire length of the presser-foot, which projections cause the joined seam to be crowded and uneven.

It is to be understood that the invention is not limited in its application to the particular type of sewing machine illustrated, and may be modified in many ways within the scope of the appended claims. 120

Having thus set forth the nature of the invention, what I claim herein is—

1. In a sewing machine, in combination, 125
stitch-forming mechanism including a reciprocating needle, a presser-foot including a shank and a sole-piece hinged thereto, and trimming mechanism including cutting 130

means supported by said presser-foot at a point between the front end of said sole-piece and the needles.

2. In a sewing machine, in combination, 5 stitch-forming mechanism including a reciprocating needle, a presser-foot including a shank and a slotted sole-portion hinged thereto intermediate its ends, and trimming mechanism including cutting means supported by said shank above said slot and adapted to act upon the work guided by said slot in advance of said needles, said sole-portion being set at a lower level than said shank.

3. In a sewing machine, in combination, 15 stitch-forming mechanism including a reciprocating needle, a presser-foot including a relatively fixed portion and a sole-portion hinged thereto and projecting in advance thereof, and trimming mechanism including trimmer blades supported by said relatively fixed portion and adapted to act upon the work in advance of said needles.

4. In a sewing machine, stitch-forming mechanism, a presser-foot having a fixed 25 portion and a sole-piece movable relatively thereto and slotted to guide upturned marginal portions of material, a trimmer-blade carried by the fixed portion and disposed above the slot in the sole-piece, and a coacting trimmer-blade mounted independently of the presser-foot and movable relatively to the first blade and also therewith, the sole-piece having its lower surface set at a lower level than the lowest part of said fixed 30 portion.

5. A trimmer for sewing machines comprising a presser-foot having a fixed portion and a sole-piece with a needle-aperture, trimming mechanism disposed above said sole-piece and comprising cutter-blades disposed in front of said needle-aperture and adjacent thereto, said sole-piece and trimming mechanism being spaced apart vertically and relatively movable vertically, and said sole-piece 45 having its lower surface set at a lower level than the lowest part of said fixed portion.

6. A trimmer for sewing machines comprising a presser-foot having a hinged sole-piece, a needle-aperture in said sole-piece, 50 and a trimming mechanism disposed between said aperture and the toe of said sole-piece and spaced from the sole-piece.

7. A trimmer for sewing machines comprising a presser-foot having a shank and a 55 pivotally mounted sole-piece, a portion of said sole-piece being recessed, a cutter-blade fixed to said shank and spaced above said recess when operating on work of uniform thickness, and a movable cutter-blade co-acting with the first-mentioned blade, said sole-piece having its lower surface set at a lower level than the lowest part of said shank.

8. In a sewing machine, a presser-foot 65 having a pivotally mounted sole-piece and a

relatively fixed extension, said sole-piece being recessed adjacent said extension, a ledger-blade carried by said extension and spaced above said recess, an independently and yieldingly mounted cutter-blade in engagement with said ledger-blade, and means for actuating said cutter-blade, said sole-piece having its lower surface set at a lower level than the lowest part of said fixed extension. 75

9. A presser-foot including a slotted sole-piece having the portions on the opposite sides of said slot rigidly connected together and adapted to exert the pressure of the presser-foot upon the work, a needle-aperture in rear of such slot, a cutter mechanism disposed in front of said aperture and in operative relation to said slot to trim the work projecting therethrough, said cutter mechanism and the slotted portion of the sole-piece being spaced apart and relatively movable vertically as the machine sews work of irregular thickness. 80

10. In a trimmer for sewing machines, a presser-foot comprising a sole-piece adapted 90 to sustain the presser-foot and an extension, said sole-piece being slotted to form toe portions and having a needle-aperture in rear of said slot, one of said toe portions having a recess, a cutter-blade carried by said extension and extending over said recess, and a second cutter-blade mounted independently of the presser-foot and coacting with said first blade, said blades and the slotted portion of the sole-piece being spaced apart and 95 relatively movable vertically as the machine sews work of irregular thickness. 100

11. In a sewing machine, stitch-forming mechanism, a throat-plate having a flat work-supporting surface, a presser-foot 105 opposed throughout its length to said flat work-supporting surface, work-trimming mechanism cooperating therewith, and means including a pivoted sole-piece for the presser-foot extending forwardly of the trimming mechanism and connected to gradually lift and lower the trimming mechanism relative to the throat-plate as a cross-seam passes under the presser-foot. 110

12. In a sewing machine, a presser-foot 115 including a pivotally mounted sole-portion, trimming means, the forward end of said sole-portion extending under the trimming means and being movable about its pivot toward and from the trimming means and 120 slotted to guide the work thereto.

13. In a sewing machine, a presser-foot including a relatively fixed extension and a movably mounted sole-piece provided with a needle aperture, trimming mechanism 125 mounted on the fixed extension, and said sole-piece provided with means in front of the needle aperture for guiding the work to the trimming mechanism.

14. In a sewing machine, a presser-foot 130

comprising a body-portion and a sole-piece pivoted at a fixed level relative to the said body-portion and adapted to maintain the body-portion substantially out of contact relation with the work, and a trimming mechanism secured to the body-portion and arranged to operate transversely of the line of seam-formation.

15. In a sewing machine, a presser-foot comprising a body-portion and a sole-portion pivoted intermediate its ends at a fixed

level relative to the body-portion and adapted to maintain said body-portion substantially out of contact with the surface of the work, and a trimming mechanism sustained 15 in substantially fixed relation to the body-portion and arranged to operate crosswise of the seam.

In testimony whereof, I have signed my name to this specification.

ALBERT H. DE VOE.
